(74) *Attorney, Agent, or Firm* — Knobbe, Martens, Olson & Bear, LLP

(57) **CLAIM**

The ornamental design for a waterjet apparatus, as shown and described.

DESCRIPTION

FIG. 1 is a top side isometric view of a first embodiment of the design for a waterjet apparatus;

FIG. 2 is a bottom side isometric view thereof;

FIG. 3 is a cross sectional top-side isometric view thereof;

FIG. 4 is a partially exploded top-side isometric view thereof;

FIG. 5 is a first side view thereof;

FIG. 6 is a second side view thereof;

FIG. 7 is a third side view thereof;

FIG. 8 is a fourth side view thereof;

FIG. 9 is a top view thereof; and

FIG. 10 is a bottom view thereof.

FIG. 11 is a top-side isometric view of a second embodiment of the design for a waterjet apparatus;

FIG. 12 is a bottom-side isometric view thereof;

FIG. 13 is a first side view thereof;

FIG. 14 is a second side view thereof;

FIG. 15 is a third side view thereof;

FIG. 16 is a fourth side view thereof;

FIG. 17 is a top view thereof; and

FIG. 18 is a bottom view thereof.

FIG. 19 is a top-side isometric view of a third embodiment of the design for a waterjet apparatus;

FIG. 20 is a bottom-side isometric view thereof;

FIG. 21 is a cross-sectional top-side isometric view thereof;

FIG. 22 is a first side view thereof;

FIG. 23 is a second side view thereof;

FIG. 24 is a third side view thereof;

FIG. 25 is a fourth side view thereof;

FIG. 26 is a top view thereof; and,

FIG. 27 is a bottom view thereof.

The broken line showing of portions of the waterjet apparatus is included for the purpose of illustrating and forms no part of the claimed design.

1 Claim, 21 Drawing Sheets
